CAP FOR COLLAPSIBLE METAL CONTAINERS

Filed Jan. 3, 1923

INVENTOR
JAMES EARL ANDERSON

Arthur L. Lee
Atty.

UNITED STATES PATENT OFFICE.

JAMES EARL ANDERSON, OF SAN FRANCISCO, CALIFORNIA.

CAP FOR COLLAPSIBLE METAL CONTAINERS.

Application filed January 3, 1923. Serial No. 610,446.

To all whom it may concern:

Be it known that I, JAMES EARL ANDERSON, a citizen of the United States, residing in the city and county of San Francisco and State of California, have invented a new and useful Improvement in a Cap for Collapsible Metal Containers, of which the following is a specification.

My invention relates to improvements in caps for collapsible metal tubes and the like and is directed particularly to a device attachable upon the ordinary collapsible container to replace the usual threaded cap.

The primary object is to provide an improved cap for collapsible metal containers.

Another object is to provide an improved device adapted to facilitate the opening and closing of a container of the character described.

A further object is to provide an improved device which will effectively close the container to protect the contents from deterioration and to maintain the same in a sanitary condition.

A still further object is to provide a device which may be readily removed from a container when the contents have been exhausted and applied upon a new tube.

A further object is to provide a device of simple construction which can be readily stamped from sheet metal and marketed at a nominal cost.

I accomplish these and other objects by means of the device disclosed in the drawings forming a part of the present specification wherein like characters of reference are used to designate similar parts throughout said specification and drawings, and in which:

Fig. 1 is a side elevation of my invention, as applied upon a collapsible metal tube container.

Fig. 2 is a vertical section of my improved cap as applied upon the tube.

Fig. 3 is a broken elevation of the tube showing the back of the cap.

Fig. 4 is a plan view of the device as shown in Fig. 1.

Referring to the drawings the numeral 1 is used to designate in general a container such as the collapsible metal containers in which tooth paste, and similar toilet preparations are commonly sold. Such containers, as is well known, are commonly pro-

vided with a threaded dispensing tip 2 arranged to receive a cap screwed thereon to close the tube, it being necessary to remove the cap before the substance within the tube can be dispensed. This cap is frequently dropped and lost, or becomes bent to such a degree that it can no longer be applied upon the tip 2. Furthermore, the threads of the tip, which is made of lead or other soft metal, become coated with the substance contained within the tube, or become damaged to such an extent that application of the cap becomes impractical.

To overcome these difficulties and to facilitate the opening and closing of the tube, I have provided an improved cap consisting of a cover member 3 stamped from sheet metal to fit over the top of the tube. An aperture 4 is formed in the cover to receive the tip 2, when the cover is applied upon the tube. A flange 6 formed from a plurality of segments turned downwardly from the cover is arranged to detachably engage the top of the tube. The segments are so shaped that when the flange 6 is forced over the end of the tube, the segments will be sprung outwardly to pass over the top edge of the tube, which is made of relatively heavy metal of rigid construction, and then return to normal position to engage the tube along the top edge thereof.

An extension 7 is formed upon one side of the cover 3 and arranged to conform with the side of the tube. Arcuate arms 8 are formed upon the end of the extension to engage the sides of the tube, said arms preferably extending slightly beyond the center of the tube and being made with a slight spring resilience to maintain engagement with the tube whereby distortion of the upper portion of the tube may be prevented and a suitable gripping surface provided for holding the tube.

Lugs 9 are stamped out from the extension 7 and bent outwardly into parallel spaced relation. Apertures 11 are formed in the lugs 9 to receive bearings 12 carried upon the sides of a stopper member 13 pivotally mounted thereon. The stopper member 13 is provided with an extension 14 shaped to extend over the end of the dispensing tip 2 and preferably provided with a slightly recessed pad 16 made of rubber, cork, or other suitable material to be pressed

2 firmly over the opening in the dispensing tip.

An actuating lever portion 17 is formed upon the opposite end of the member 13 and arranged to be depressed against the pressure of a spring 18 secured upon the extension 7 to move the member 13 pivotally upon the bearings 12 and thereby move the extension 14 out of engagement with the dispensing tip as shown in dotted lines in Fig. 1 of the drawings. The spring 18 is secured upon the back of the extension 7 and arranged to normally hold the stopper member 13 in closing relation to the dispensing tip and to return the member to the closing position when the actuating lever 17 is released.

The substance enclosed within the tube is dispensed in the usual manner by exerting a slight pressure upon the sides of the tube, the extension 7 and arms 8 being readily gripped in such manner as to depress the lever portion and thereby move the extension 14 away from dispensing tip and at the same time permit the fingers of the user to be pressed against the tube. When sufficient substance has been dispensed the user has only to release his grip upon the tube and stopper and the spring will move the extension 14 back into engagement with the tip to effectively close the tube and prevent the displacement of further quantities of the substance. The movement of the stopper member 13 is made sufficient to permit a brush to be applied closely to the tip to receive the dispensed substance.

From the above description it will be seen that I have provided an improved cap for tubes of the character described which may be stamped from sheet metal and assembled at a nominal cost and which may be conveniently removed from one tube and applied upon another so that a single cap may be made to serve indefinitely, thereby affording an effective closing device at an extremely low cost to the user. The construction illustrated in the drawings is, of course, subject to modification in many ways and may be made to present any desired ornamental appearance. I, therefore, do not wish to restrict myself to the precise form disclosed in the drawings, but desire to avail myself of such modifications as may fall within the scope of the appended claims.

Having thus described my invention, what I claim as new and desire to secure by Letters Patent is:

1. A cap for collapsible metal tubes and the like comprising a cover having a central aperture adapted to receive the dispensing tip of a tube, and provided with a flanged edge detachably engaging the top of said tube; and a stopper pivotally mounted upon said cover for normally closing the opening in said dispensing tip.

2. A cap for collapsible metal tubes and the like comprising a cover having a central aperture adapted to receive the dispensing tip of a tube; a flange formed upon the edge of the cover to detachably engage the top of the tube; an extension formed upon the cover to engage the tube at a point below the top thereof; and a stopper pivotally mounted upon said extension and arranged to normally close the opening in the dispensing tip.

3. A cap for collapsible tubes and the like comprising a cover having a central aperture adapted to receive the dispensing tip of a tube; a flange formed in a plurality of expandible segments upon the edge of the cover to detachably engage the top of the tube; a stopper pivotally mounted upon said cover; and a spring arranged to normally hold said stopper in engagement with the dispensing tip to close the same.

4. A cap for collapsible tubes and the like comprising a cover having a central aperture adapted to receive the dispensing tip of a tube; a flange formed in a plurality of expandible segments shaped to detachably engage the top of the tube when forced thereover; an extension formed upon the cover upon one side of the tube, said extension being provided with laterally extending portions shaped to engage the sides of the tube; and a stopper pivotally mounted upon the extension and shaped to extend into engagement with the dispensing tip; and arranged to be moved away from said tip to permit substance to be dispensed therethrough.

5. A cap for collapsible tubes and the like comprising a cover having a central aperture adapted to receive the dispensing tip of a tube; a flange formed in a plurality of expandible segments shaped to detachably engage the top of the tube when forced thereover; an extension formed upon the cover upon one side of the tube, said extension being provided with laterally extending portions shaped to engage the sides of the tube; and a stopper pivotally mounted upon the extension and shaped to extend into engagement with the dispensing tip and arranged to be moved away from said tip to permit substance to be dispensed therethrough; and a spring mounted between the cover and the stopper to normally hold said stopper in engagement with the tip.

6. A cap for collapsible metal tubes and the like comprising a cover stamped from sheet metal and having a central aperture arranged to receive the dispensing tip of a tube; a flange shaped upon the edge of the cover and formed in a plurality of segments adapted to be expanded to engage the top of the tube; an extension formed upon one side of the cover and arranged to conform to a side of the tube; arcuate arms formed upon the end of said extension to engage the sides

of the tube; lugs stamped from the extension and bent to outwardly extending parallel position; and a stopper pivotally mounted between said lugs, said stopper being provided at one end with a tube closing portion arranged to engage the end of the dispensing tip to close the same, and pro-

vided with an actuating portion whereby said closing portion may be moved to disengage the dispensing tip to permit substance to be dispensed therethrough.

In witness whereof I hereunto set my signature.

JAMES EARL ANDERSON.
